O. KRAUS.
CONSTANT LEVEL OIL TANK.
APPLICATION FILED MAR. 31, 1919.

Patented Nov. 2, 1920.

UNITED STATES PATENT OFFICE.

OTTO KRAUS, OF NEW YORK, N. Y., ASSIGNOR TO KRAUS ENGINE COMPANY, OF NEW YORK, N. Y., A CORPORATION OF NEW YORK.

CONSTANT-LEVEL OIL-TANK.

1,357,877.

Specification of Letters Patent.

Patented Nov. 2, 1920.

Original application filed March 19, 1918, Serial No. 223,264. Divided and this application filed March 31, 1919. Serial No. 286,373.

To all whom it may concern:

Be it known that I, OTTO KRAUS, a citizen of the United States of America, residing at the borough of Manhattan, in the city, 5 county, and State of New York, have invented certain new and useful Improvements in Constant-Level Oil-Tanks, of which the following is a specification, reference being had to the accompanying drawings.

10 This invention relates to improvements in liquid-fuel tanks and particularly to improvements in tanks in which the liquid fuel is maintained at a constant level and which are used in connection with furnaces 15 wherein hydrocarbon oil is burned and the products of combustion are mingled with water vapor or steam to form a working fluid for motors. An object of this invention is to provide a liquid-fuel tank of the 20 constant-level type which will be simple in construction and comparatively cheap in manufacture, and which will prove efficient and durable in operation and use, and low in cost of first installation and of repairs.

25 In the drawings illustrating the principle of this invention and the best mode now known to me of applying that principle, Figure 1 is a central, longitudinal section of a furnace equipped with the constant-level 30 liquid-fuel tank; Fig. 2 is a transverse vertical section on the line 2—2 of Fig. 1; Fig. 3 is a fragmentary section on the line 3—3 of Fig. 1 and illustrates one form of valve mechanism for controlling the overflow of 35 oil from the fuel-tank; Fig. 4 is a fragmentary sectional view of a modified form of valve mechanism for controlling the overflow of the liquid fuel; and Fig. 5 is a section on the line 5—5 of Fig. 4.

40 Compressed air flows through the conduit *a*, past the spring-controlled valve *b*, and into the combustion-chamber *c* (Figs. 1 and 2). Some of the compressed air flows from the conduit *a* through the air-passage *d* into 45 the annular chamber *e* that surrounds the casing *f* of the needle-valve *g*. The annular chamber *e* communicates through the air-passage *h'* with the air-space *h* above the level of the liquid hydro-carbon *i* in the 50 fuel-tank *j*, whereby the oil *i* is subjected to the pressure of the compressed air and is thereby forced upwardly through the pipe *k* and past the needle-valve *g*.

To maintain constant the level of the

liquid fuel *i* in its tank *j*, the following arrangement of parts is provided: Oil flows into the tank *j* through the oil-pipe *m* that leads from a force-pump (not shown). The oil *i* supports by its buoyant effort, a float *n*, from which extends a pair of arms *o* that are connected, by a pivot-pin *p* to the lateral wall *j'* of the tank *j* and are, therefore, free to swing thereon (Figs. 1 and 3). Through the bottom of the tank *j*, there passes an overflow-pipe *q*, the inner or upper end of which is closed, except for the perforations *r*, hereinafter referred to, and is formed with a laterally-extending, annular flange *s*. Below the latter, there is formed, on the pipe *q*, a collar *t*, between which and the flange *s* the pipe *q* is formed with a circular series of perforations *r*. Over this part of the pipe *q*, there is slipped a slidably-mounted sleeve-valve *u* that is formed with a pair of laterally-projecting ears *v*, against which press upwardly the arms *o* extending from the float *n*. The sleeve-valve *u* is further formed with a series of oil-ports *u'* which, when the valve is raised to the upper limit of its travel (determined by the annular flange *s*) through the medium of the float-actuated arms *o* pressing against the ears *v* on the valve *u*, come into register with the holes *r* (Figs. 1 and 3), whereupon oil is free to flow from the tank *j*, through the oil-ports *u'* and the holes *r*, into the overflow-pipe *q* and therethrough back to the source of the oil-supply. By this arrangement of parts, the liquid fuel *i* is maintained at a constant level in its reservoir *j*. It is to be noted that the oil-ports *u'* do not register with the perforations *r*, until the level of the oil *i* in its reservoir *j* lies at a substantial distance above the closed inner end of the overflow-pipe *q*, whereby any escape 95 therethrough of the compressed air from the air-space *h* is avoided.

A modified form of the overflow arrangement just described is illustrated in Figs. 4 and 5, wherein there is shown a sleeve-valve *u''* that is rotatably mounted on the inner end of the horizontally-disposed part *w'* of the overflow-pipe *w* and connected, to the float *n'*, by means of the arm *o'*, and held in place, on the pipe *w'*, by the screw *o''*. The part *w'* of the overflow-pipe *w* is formed with a series of perforations *w''*, with which are arranged to register the oil-ports *u'* of

the sleeve-valve u'' , when the float n' has reached the permissibly highest point of its travel, whereupon the surplus oil is permitted to flow away through the overflow 5 pipe w .

As has been hereinbefore described, the pressure of the compressed air in the air-space h above the surface of the oil i in the oil-reservoir j , forces the oil therefrom upwardly through the oil-pipe k and past the needle-valve g ; and this stream of oil is struck by a stream of compressed air flowing from the annular chamber e through the inclined air-passage e' , whereby the oil is atomized and issues from the orifice x' of the atomizer x in a fine spray, as is indicated in Fig. 1. Around this orifice x' , there is fitted the smaller end of a trumpet-shaped mouth-piece y , between the edge of the larger or discharge end of which and the inner wall of the combustion-chamber c there exists an interval y' , through which escapes the compressed air that flows past the spring-controlled valve b . Thus there is formed a combustible mixture of oil and air in the combustion-chamber c , which mixture is ignited by the hot filament of an electric igniter z . The burning oil passes through the reignition grating 2 and flows downwardly through the upright flue 3 the lower end of which projects into the drum or box 4 through an opening 4' in the top thereof. The flue 3 and drum 4 are inclosed in the lower part of the steam-generator 5, wherein 35 there are hung chains 6 the links of which present an extensive surface. The side-wall of the box 4 is formed with outlets 4'' through which escape the products of combustion coming from the flue 3.

40 In the front wall A' of the furnace A , there are formed water-chambers 7 the water in which absorbs the heat from, and thereby keeps cool, the walls bathed by it. To these water-chambers 7, water that has, in any 45 suitable way (e. g., by being exposed to hot exhaust-gases from an engine), been pre-heated but is yet comparatively cool, is led through the water pipe 7' and water-passage 7''. From these water-chambers 7, the water 50 flows to the water-jacket space c' between the walls of the combustion-chamber c of the furnace A . In the rear wall A'' of the latter, there is formed an L-shaped water-passage 8 the front end of which communicates with 55 the water-jacket space c' and the other end of which communicates with the upper end of a water-pipe 9 that is mounted in the flue 3, which is vertically disposed and into and through which pass the products of combustion, as has hereinbefore been described. From the bottom of the drum 4, there projects a nipple or boss 10 formed with an inlet water-passage 10' and with lateral discharge 60 passages 10''. Into the inlet end of the passage 10', there fits the lower end of the water-

pipe 9. In the lower edge of the drum or box 4, there are formed cuts 4'' to permit the upward flow of the water that issues from the outlet passages 10.''

When the products of combustion rush 70 from the drum 4 through the outlets 4'' therein, some of the water in the lower part of the steam-generator chamber 5 is taken up and carried along with the products of combustion. In flowing upwardly to the outlet 75 opening 5' of the chamber 5, the stream of hot gases with its entrained moisture, contacts with the extensive surface of the links 6 and there results an interchange of heat between the hot gases and their entrained 80 moisture, whereby the moisture becomes converted into steam.

The lower end of the steam-generator chamber 5 is formed with a boss 5'' through which extends a passage 5'' that lies, practically speaking, in prolongation of the water-passage 10' and is closed at its discharge end by means of a drain-cock 11. To the boss 5'', there is fastened a starting-cup 12, which is filled at starting, with alcohol or like combustible, the burning of which produces heat sufficient to generate steam from the water in the bottom of the chamber 5.

The maintenance of a constant level of oil in the fuel-tank j tends to maintain the pressure of the air and the rate of feed of the oil constant and to enhance the evenness and smoothness of working of the entire furnace system and the production of working fluid thereby.

This application is filed as a divisional application under my pending application, Serial No. 223264, filed March 19, 1918.

I claim:

1. An oil-burning furnace including a combustion chamber; a fuel-reservoir; means for supplying air under pressure to the oil in the fuel-reservoir; a valve-controlled conduit which leads oil from the fuel-reservoir to the combustion-chamber; an overflow-pipe 105 which extends into the oil-reservoir and the inlet-end of which is formed with perforations; a valve which is slidably fitted on the inlet-end of the overflow pipe and is formed with oil-ports that are arranged to register 110 with the perforations in the overflow-pipe when the oil-ports and perforations are sealed by the oil in the fuel-reservoir against the escape of the air under pressure therein; and a float that controls the valve.

2. An oil-burning furnace including a combustion - chamber; a fuel - reservoir; means for supplying air under pressure to the oil in the fuel-reservoir; a valve-controlled conduit which leads oil from the fuel-reservoir to the combustion-chamber; an overflow-pipe which extends into the oil-reservoir and the inlet-end of which is formed with perforations; a valve which is slidably fitted on the inlet-end of the overflow-pipe 115 120 125 130

and is formed with oil-ports that are arranged to register with the perforations in the over-flow-pipe when the oil-ports and perforations are sealed by the oil in the fuel-
5 reservoir against the escape of the air under pressure therein; means carried by the inlet-end of the overflow-pipe for limiting the travel of the valve thereon; and a float that controls the valve.

Signed in the presence of the two under-¹⁰ signed witnesses at the borough of Manhat-
tan, in the city, county and State of New
York, this 28th day of March, A. D. 1919.

OTTO KRAUS.
